UNITED STATES PATENT OFFICE.

GEORGE HUNT, OF BLOOMFIELD, NEW JERSEY, ASSIGNOR TO THE CONSOLIDATED SAFETY PIN COMPANY, OF SAME PLACE.

DESIGN FOR A SAFETY-PIN.

SPECIFICATION forming part of Design No. 32,206, dated February 6, 1900.

Application filed January 11, 1900. Serial No. 1,150. Term of patent 14 years.

To all whom it may concern:

Be it known that I, GEORGE HUNT, a citizen of the United States, residing in Bloomfield, in the county of Essex, State of New Jersey, have invented and produced a certain new and original Design for a Safety-Pin, of which the following is a specification, reference being had to the accompanying drawings, forming a part hereof.

This invention relates to safety-pins formed of a continuous piece of wire and having a back member with a hood or shield and a point member, which engages said hood or shield when the pin is in use; and the invention consists in the design therefor shown in the accompanying drawings, in which—

Figure 1 is a front elevation of a safety-pin which embodies the design, and Fig. 2 is an end elevation thereof as seen from the right hand in Fig. 1.

The point member *a*, the coil *b* at one end, and the hood or shield *c* at the other end present substantially the usual appearance, as does also the back member *d*, except for an apparent break in its continuity at about the middle of its length, as at *e*. As seen in front elevation in Fig. 1, the pin-wire forms a substantial circle *f*, approximately tangent to the

back member at its middle point, such circle being nearly divided by substantially straight 30 portions *g*. As seen in end elevation, as in Fig. 2, the plane of the circular portion *F* and the plane of the point and back members are practically parallel, but offset, the portions *g* being connected by a sharp curve *h* and other 35 similar and nearly parallel portions *i* with the back member *d*, from which such portions *i* depend, the said portions *g* and *i*, with the curve *h*, forming, as seen in end view, a U-shaped connection between the back member 40 *d* and the circular portion or head *f*.

The characteristic feature of the design is the generally circular head *f*, as seen in front elevation, with a U-shaped connection to the back member of the pin, as seen in end elevation. 45

I claim as my invention—

The design for a safety-pin, substantially as shown and described.

This specification signed and witnessed this 50 5th day of January, A. D. 1900.

GEORGE HUNT.

In presence of—

GEORGE P. FARMER,
N. E. MATTHEWS.
